UNITED STATES PATENT OFFICE.

WIRT M. REESE, OF CLEVELAND, OHIO.

DESIGN FOR A CASKET HANDLE-PLATE.

44,936.

Specification for Design.

Patented Nov. 25, 1913.

Application filed March 21, 1912. Serial No. 685,348. Term of patent 7 years.

To all whom it may concern:

Be it known that I, WIRT M. REESE, a citizen of the United States, residing at Cleveland, in the county of Cuyahoga and State of Ohio, have invented a new, original, and ornamental Design for a Casket Handle-Plate, of which the following is a specification, reference being had to the accompanying drawings, forming part thereof.

In the drawings, Figure I, is a plan view and Fig. II, is a side elevation.

What I claim is:

The ornamental design for a casket handle plate, as shown.

Signed at Cleveland in the county of Cuyahoga and State of Ohio this 12th day March 1912.

WIRT M. REESE.

Witnesses:

JOHN J. DONNELLY,
ALBERT B. DONNELLY.
